PRESET FREQUENCY REJECTION IN INTER-MEDIATE FREQUENCY AMPLIFIERS

Emerrick Toth, Cheverly, Md.

Application January 29, 1941, Serial No. 376,408

6 Claims. (Cl. 178—44)

(Granted under the act of March 3, 1883, as amended April 30, 1928; 370 O. G. 757)

This invention relates to a tuned amplifier circuit arranged to automatically reject certain undesired frequencies in the neighborhood of the peak frequency of the circuit. It is an object of this invention to provide such a circuit which will be automatically tuned to a predetermined rejection frequency or frequencies when it is tuned to the desired peak frequency.

Referring now to the drawing:

Fig. 1 is a diagrammatic view of a circuit embodying the invention and arranged to reject a frequency above the peak frequency of the circuit.

Fig. 2 is a view similar to that shown in Fig. 1 showing the circuit arranged to reject a frequency below the peak frequency of the circuit.

Fig. 3 is a diagrammatic view of the circuit similar to that shown in Fig. 1 but arranged for rejection both above and below the peak frequency.

In the drawing reference characters V_1 and V_2 refer to a pair of amplifier tubes, the plate circuit of V_1 being coupled to the grid circuit of V_1 by means of an I. F. coupling device or transformer having a secondary L_4 and a primary L_3 . The reference character T_1 indicates the complete coupling circuit.

The primary L_3 lies in one branch of a tuned circuit containing inductance L_1 and capacitance C_1 in its other branch. The circuit branch L_1C_1 is tuned to the desired rejection frequency. The secondary L_4 lies in one branch of a similar circuit, the other branch being formed by inductance L_2 and variable capacity C_2 . The circuit branch L_2C_2 is tuned to the same frequency as L_1C_1 or to another desired rejection frequency. Both frequencies must lie above the peak frequency of the I. F. transformer. The values of L_1 and C_1 must be chosen to resonate at the desired rejection frequency, and must have a combined reactance at the I. F. peak frequency that will be capacitive and of such value as to resonate with L_3 at the I. F. peak frequency. Thus L_1C_1 will effectively bypass L_3 at the rejection frequency and will tune it to parallel resonance at the peak frequency. The same will be true of L_2C_2 and L_4 . L_3 and L_4 can be coupled to the degree desired for the peak band width required in the I. F. amplifier system. This coupling may be inductive or capacitive or both. Tuning to the desired peak frequency will be accomplished by varying C_1 and C_2 .

In Fig. 2 is shown a circuit arrangement for a rejection frequency or frequencies below the

peak frequency of the transformer. L_1C_1 and L_2C_2 again form the rejector circuits, L_3 and L_4 having been replaced by capacitors C_3 and C_4 tuning with the equivalent inductive reactance of L_1C_1 and L_2C_2 respectively at the I. F. peak frequency. C_5 provides the coupling capacity necessary for the band width required.

Fig. 3 shows a circuit arrangement for combined rejection below and above peak frequency. In this circuit L_1C_1 forms the rejector circuit for a frequency above peak frequency and L_2C_2 forms a rejector circuit for a frequency below peak frequency. L_3 is an inductance resonating with the equivalent capacity reactance of L_1C_1 at peak frequency and C_4 is a capacitor resonating with the equivalent inductive reactance of L_2C_2 at the peak frequency. C_5 is a coupling capacitor.

The required shielding is shown in the figures by dotted lines.

By use of the circuits shown, the transformer is automatically tuned to the predetermined rejection frequency or frequencies when it is peaked by adjusting C_1 and C_2 at the peak frequency.

While the disclosure has been restricted to three embodiments, the invention is not to be considered as limited thereby but only by the scope and limitations of the appended claims.

The invention described herein may be manufactured and/or used by or for the Government of the United States of America for governmental purposes without the payment of any royalties thereon or therefor.

I claim:

- 35 1. In an I. F. amplifier circuit including a resonant coupling means having one inductive and one capacitive element, means for rejecting a pair of undesired frequencies in the neighborhood of the peak frequency of said coupling means, one of said undesired frequencies being above and the other of said frequencies being below the said peak frequency of said coupling means, comprising a tuned circuit shunted across each element of said coupling means, each of said tuned circuits being tuned to one of said rejection frequencies, the L. C. values of said tuned circuit which is shunted across the inductive element of said coupling means being so selected as to have, at the peak frequency of said coupling means, a combined reactance which is capacitive in nature and of such value as to resonate with said inductive element, the L. C. values of said tuned circuit which is shunted across said capacitive element of said coupling means being so selected as to have at the peak frequency of said

coupling means, a combined reactance which is inductive in nature and of such value as to resonate with said capacitive element of said coupling means.

2. In an I. F. amplifier circuit including a resonant coupling means having a pair of inductances as elements, means for rejecting a pair of undesired frequencies in the neighborhood of and above the peak frequency of said coupling means, comprising a tuned circuit shunted across each of said elements of said coupling means, each of said tuned circuits being tuned to one of said rejection frequencies, the L. C. values of each of said tuned circuits being so selected as to have at the peak frequency of said coupling means, a combined reactance which is capacitive in nature and of such value as to resonate with said element of said coupling means across which said tuned circuit is shunted.

3. In an I. F. amplifier circuit including a resonant coupling means having a pair of capacitors as elements, means for rejecting one or a pair of undesired frequencies in the neighborhood of and below the peak frequency of said coupling means, comprising a tuned circuit shunted across each of said elements of said coupling means, each of said tuned circuits being tuned to said rejection frequency, the L. C. values of each of said tuned circuits being so selected as to have, at the peak frequency of said coupling means, a combined reactance which is inductive in nature and of such value as to resonate with said element of said coupling means across which said tuned circuit is shunted.

4. In an I. F. amplifier circuit, a transformer assembly comprising a pair of coupled circuits resonant at the predetermined peak frequency of said transformer, a pair of inductances and a capacitor in each of said circuits, means dividing each of said circuits into two parallel branches

across a voltage source and a load respectively, one of said branches in each of said circuits containing one of said inductances and said capacitor, said one of said inductances and said capacitor being resonant at a predetermined frequency near said peak frequency.

5. In an I. F. amplifier circuit, a filter assembly comprising a pair of coupled circuits resonant at the predetermined peak frequency of said filter, a pair of capacitors and an inductance in each of said circuits, means dividing each of said circuits into two parallel branches across a voltage source and a load respectively, one of said branches in each of said circuits containing one of said capacitors and said inductance, said one of said capacitors and said inductance being resonant at a predetermined frequency near said peak frequency.

6. In an I. F. amplifier circuit, a filter assembly for use as a plate load for a vacuum tube of said circuit comprising a first circuit and a second circuit coupled thereto, said circuits being resonant at the predetermined peak frequency of said filter, a pair of inductances and a capacitor in said first circuit, means dividing said circuit into two parallel branches across a voltage source, one of said branches containing one of said inductances and said capacitor, said one of said inductances and said capacitor being resonant at a predetermined frequency above said peak frequency, a pair of capacitors and an inductance in said second circuit, means dividing said second circuit into two parallel branches across a load, one of said branches containing one of said capacitors and said inductance, said one of said capacitors and said inductance being resonant at a predetermined frequency below said peak frequency.
